UNITED STATES PATENT OFFICE.

LOUISE S. ALLEN, OF CIRCLEVILLE, OHIO.

HANGER FOR SPRING-CLAMPS.

1,064,952.

Specification of Letters Patent. Patented June 17, 1913.

Application filed January 6, 1912. Serial No. 669,633.

To all whom it may concern:

Be it known that I, LOUISE S. ALLEN, citizen of the United States, residing at Circleville, in the county of Pickaway and State 5 of Ohio, have invented certain new and useful Improvements in Hangers for Spring-Clamps, of which the following is a specification.

My invention relates to hangers of that 10 class wherein a spring clamp is employed, and has for its object to provide in connection with the spring clamp, a supporting or hanging device which may be very cheaply made, and which is adapted to be applied 15 to spring clamps already in use, or else to be manufactured in connection with the clamps.

A further object is to provide a hanger to be used in connection with the clamps above 20 described, constructed of a single piece of wire, so bent that it may be readily applied to clamps and firmly engage the same through its own resilience, no implement being necessary in order to apply the hanger 25 to the clamp and no modification being necessary in the clamp itself.

A further object is to so form the hanger above referred to as to provide means for locking the hanger upon the clamp and thus 30 preventing its accidental detachment while permitting it to be readily detached intentionally.

My invention is illustrated in the accompanying drawing wherein:

35 Figure 1 is a perspective view of my, hanger applied to a clamp. Fig. 2 is a face view of the hanger showing the manner of applying the same to the clamp, the clamp being shown in dotted lines. Fig. 3 is a detail perspective view of the hanger showing 40 the same in its normal position before being applied to the clamp. Fig. 4 is a face view of the hanger showing the position taken by the parts when the hanger is applied 45 to the clamp, the clamp being shown in dotted lines. Fig. 5 is a perspective view of the hanger and clamp but showing the hanger supporting the clamp in a substantially horizontal position.

50 Corresponding and like parts are referred to in the following description and indicated in all the views of the accompanying drawing by the same reference characters.

In the drawings I have illustrated a clamp 55 composed of two clamping jaws 2, these jaws being recessed about midway their

length as at 3 so as to receive the coil 4 of the spring 5, the ends thereof extending along the sides of the clamping jaws and being bent outward and laterally to engage 60 the outer sides of the clamping jaws near the ends thereof. It is to be noted that the pivot of the clamp is formed of the coil 3 and that this coil is open at the ends. This form of clamp is old and by itself forms no 65 part of my invention.

In order to provide means for hanging the clamp above described, and in order to provide a device which is readily attachable to or detachable from such a clamp, I provide 70 a hanger of the form shown in Fig. 3. This hanger is composed of a single piece of wire 6 which may be of any desired size and length and which has the proper resiliency. The length of wire is bent intermediate its 75 ends to form an open loop 7 having its extremities outwardly bent as at 8. The resilience of the wire is such as to hold the extremities of the legs of the loop apart from each other, and the angular bends 80 extending in opposite directions.

When it is desired to apply the hanger to the clamp, the loop 7 is compressed between the thumb and finger and the legs of the loop caused to cross each other, as shown in 85 Fig. 2. The loop 7 is compressed to such an extent that the terminal ends 8 are opened or spread apart from each other sufficiently to permit the insertion of the clamp between these terminal ends. When the terminal 90 ends 8 are opposite the coil 3 of the clamp, the pressure on the loop is relieved and the resilience of the loop forces the terminal ends 8 into the coil 3. When in position within the coil 3, it will be seen that the terminal ends overlap each other to a considerable extent, thus providing a double bearing 95 or support for the clamp along practically the whole length of the coil 3.

It will be seen that when once in position, 100 the hanger can not readily be detached from the clamp and that the clamp provides means whereby the hanger may be supported and used as a means for displaying articles, or for hanging articles within a closet. 105

It will be seen that the clamp may be made entirely separate from the hanger and afterward applied thereto, and that the hangers may be removed or applied to the clamps whenever desired to use the clamps for supporting objects. It may be further pointed out that the loop 7 lies in the same plane as 110

the jaws 2 so that the hanger forms no obstruction to the opening of the clamp and need not be removed from the clamp in order to open the jaws. Further it will be seen 5 that the hanger being disposed as it is immediately above the center of the clamp, the weight placed upon the hanger will come directly downward and not to one side.

In order to provide means for holding the 10 hanger with its terminal ends opened so that it may be readily applied to the clamp, I may provide one of the legs of the loop 7 with a crimp or loop 9 of such depth that when the loop 7 is compressed to such point 15 that the terminal ends 8 will open up sufficiently to permit the clamp to be inserted between the ends, one of the legs of the loop 7 will engage in the loop 9. This engagement of one of the legs with the loop 9 will 20 hold the legs in a spaced condition ready for engagement with the clamp.

It has been attempted in a number of cases to provide means for supporting the form 25 of clamp illustrated in Fig. 1. No means have heretofore been provided, however, for supporting a single one of these clamps which may be readily attached to or detached from the clamp and which will engage the clamp at its middle so that when 30 hung up, the clamp will depend straight from the hanger.

While under ordinary circumstances, the hanger will be applied to the clamp in the manner shown in Fig. 1, it may sometimes 35 occur that it is desirable to support the clamp at an angle to the vertical, and it will be seen from Fig. 5 that this may be readily done by detaching the hanger from the

clamp and replacing it in engagement therewith, with the hanger disposed on one side 40 of the clamp in place of between the jaws. Under these circumstances, the clamp may be used for supporting cards or like articles at an angle to the vertical and be used in circumstances where a vertically hung clamp 45 would be of little or no value.

A clamp and hanger constructed as above described is particularly useful in dressing store windows but may be used for a large variety of purposes including the hanging 50 of garments.

My invention is very simple, may be cheaply made in large quantities, is readily applied or detached and is extremely convenient as it does not interfere with the ordinary use of the clamp. 55

What I claim is:

A hanger for clamping members comprising a strand of resilient material bent upon itself, the ends of said strand being disposed at right angles to the body portion, the strand being crossed to resiliently extend its offset ends within the article to be supported, there being a loop pressed out from the strand with which the oppositely disposed portion of the strand contacts to maintain the offset terminals in spaced relation in order that the hanger may be applied to the device to be supported. 60

In testimony whereof, I affix my signature 70 in presence of two witnesses.

LOUISE S. ALLEN. [L.S.]
